UNITED STATES PATENT OFFICE.

EDMOND W. T. RICHMOND, OF ROMFORD, ENGLAND.

DESIGN FOR A GAS-STOVE.

SPECIFICATION forming part of Design No. 33,928, dated January 15, 1901.

Application filed December 19, 1900. Serial No. 40,453. Term of patent 7 years.

To all whom it may concern:

Be it known that I, EDMOND WALTER TYRRELL RICHMOND, a subject of the Queen of Great Britain, residing at Summercourt, Romford, in the county of Essex, England, have invented and produced a new and original Design for Gas-Stoves, of which the following is a specification.

The accompanying drawing is a front elevation of a gas-stove embodying my design.

The leading feature of the design is the grate or fireplace opening A, having vertical side walls B, a projecting hood C, and the low fuel guard or grid D, extending across the front of the opening at the bottom thereof, be-

low which is an ornamented base portion E. The sides of the stove are beveled, being inclined rearwardly from the opening A, and are divided into ornamental panels F G, while the curved upper face is divided into ornamental panels H I J.

I claim—

The design for a gas-stove substantially as herein shown and described.

In testimony whereof I have hereunto subscribed my name.

EDMOND W. T. RICHMOND.

Witnesses:
